Primary Examiner — Marcus Jackson*(74) Attorney, Agent, or Firm* — Steven B. Phillips; Moore & Van Allen PLLC(57) **CLAIM**

We claim the ornamental design for a lamp, as shown and described.

DESCRIPTION

FIG. 1 is a side view showing a third embodiment of our new design for a lamp. Only one side view is shown since all sides are the same.

FIG. 2 is a top view of the third embodiment of our new design shown in FIG. 1.

FIG. 3 is a bottom view of the third embodiment of our new design shown in FIG. 1; and,

FIG. 4 is a perspective view of the third embodiment of our new design as shown in FIG. 1.
